(57) **CLAIM**

The ornamental design for a drawer slideway, as shown and described.

DESCRIPTION

FIG. 1 is a state of use diagram in the same direction as FIG. 2 of a drawer slideway showing my new design;

FIG. 2 is a front, right, top perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the encircled area 9 of FIG. 2;

FIG. 10 is an enlarged view of the encircled area 10 of FIG. 3; and,

FIG. 11 is an enlarged view of the encircled area 11 of FIG. 8.

The broken lines shown on the drawings depict portions of the drawer slideway that form no part of the claimed design. The dot-dash lines depict the enlarged view boundaries that do not form part of the claimed design.
